UNITED STATES PATENT OFFICE.

JOSIAH E. SYMONS, OF MILWAUKEE, WISCONSIN.

STEEL AXLE.

No. 909,963.

Specification of Letters Patent.

Patented Jan. 19, 1909.

Application filed December 16, 1907. Serial No. 406,612.

To all whom it may concern:

Be it known that I, JOSIAH E. SYMONS, a citizen of the United States, residing at Milwaukee, in the county of Milwaukee and State of Wisconsin, have invented a certain new and useful Improvement in Steel Axles, of which the following is a specification.

My invention relates to axles for vehicles, and is illustrated in the accompanying drawings, wherein—

Figure 1 is a plan view with one end in horizontal section; Fig. 2 is a side elevation of the same with one end in vertical section on a plane at one side of the meeting edges of the sheath; Fig. 3 is a side elevation of the metal sheath; Fig. 4 is a cross section on the line 4—4 of Fig. 2; Fig. 5 is a similar cross section of a modification.

Like parts are indicated by the same letter in all the figures.

A is a thin sheet metal sheath, the full length of the axle and skeins, open at its upward side between its two ends and folded to form two tapered ends.

B is a wood core the full length of the axle and skeins and projecting above the separated edges of the central portion of the sheath. The sheath is preferably crimped or grooved or ribbed at its upper edges as indicated at C, and is held upon the core by the rivets D or bolts E or otherwise as may be found best. The tapered ends of the sheath are marked for convenience A¹A¹, and the tapered ends of the core are marked for convenience B¹ B¹. The core fits the sheath snugly at all points. A bearing surface or skein is formed by the tapered tube F which is provided with a collar G and the nut H between which the hub rests. This tapered tube is held in position by the screw bolt J which enters the end of the core.

The details of construction could, of course, be greatly altered. I wish my drawing to be taken as diagrammatic as it is intended to illustrate one form only out of many which might contain my invention.

The use and operation of my device are as follows: Broadly speaking, the object is to employ a large wooden core with a thin metal sheath, and the two are permanently connected, the sheath wrapped around or folded over on the core. They may be of such nature that neither alone would be adequate to serve as an axle. Thus the wood

may be of light and relatively weak material and the sheath may be of thin easily compressible material, thus effecting a great saving on account of the quality of the wood and the quantity of the metal, and at the same time furnishing materials which can be worked together, the thin sheath being wrapped around the wood core so as to permanently unite them to form in effect an integral axle. The skein is removable by simply removing the screw bolt which holds it in position. The thin metal of the open sides of the axle is prevented from displacement by the strengthening crimp, groove or rib formed as suggested in Fig. 5. The upwardly projecting wood portion furnishes means for attachment of the other devices in connection with which the axle is to be used.

The wood portion projects upwardly from the axle so as to be accessible for securing the other parts. A very large or heavy wood axle with a very thin sheath is produced. This wood is not intended in the first instance to afford strength. It is intended to support the sheath which so supported is strong enough to carry the load. The wood is, so to speak, a former around which the load carrying member, the thin metal sheath, is placed. This gives the axle elasticity and springiness. By this means the skein is held on elastically for the nut which holds it is supported by the bolt which is driven into the wood portion of the core. The conical end of the core serves as a former around which the steel can be bent and whereby it can be easily brought to the proper shape for the wood can be easily turned to the desired form.

Broadly speaking, the essential feature of this invention is that there should be a wooden core, preferably perhaps integral or continuous, but not necessarily so, but necessarily with tapered ends of wood, and a sheet metal covering which is wrapped around the core and particularly around the tapered ends which serve as formers. The axle skeins are then forced upon these sheet metal wrappings which lie about the wooden tapered core ends, which, together with such wooden core ends, form a more or less elastic yielding end to receive the skein and accommodate itself to the interior of the skein. Such a tapering end, it will be seen, is capa-

ble of yielding under compression on all points of its surface in order to accommodate itself accurately to the interior of the skein as the latter is forced over it into position and thus the axle is completed. In the particular form in which I have designed and illustrated these two ends, they are parts of an integral and continuous core, the upper portion of which is not covered or wrapped though its lower portion is used as a former about which the sheet metal is wrapped and bent. As above explained, where I say "wood" I mean, of course, a yielding or elastic material of the general nature of wood.

One feature of my invention is realized in a structure of the class described where the sheet metal axle end is associated with a compressible core, whether that core is to be used as a former or not. In that case the skein being forced over the two, would compress them, and thus insure their perfect fit within such skein. While I prefer to use the interior core or filling as a former about which to wrap the sheath for the purpose of securing the part of my invention here referred to, this would be unnecessary. I have spoken of the core as if it were integral and continuous from end to end. This, for some portions of my invention, is not essential, though I think it is the preferred form.

In axles the skeins must be firmly secured in position. To do this the tapering spindle must be accurately fitted to the interior surface of the skein, or, in other words, the skein must be accurately fitted around its support. If the core in an axle like mine is non-compressible it would have to be turned or machine fitted and would then not be elastic. If the fitting is cast iron it will wear and reduce in effective size and hence the advantage of my compressible core inside of the compressible spindle. The core I make of wood but it might be made of other compressible or slightly elastic material.

I claim:

1. An axle comprising a two part structure consisting of a wooden core with tapered ends and a thin metal sheath inclosing the core, its ends permanently wrapped around and set in position about the tapered ends of the core to form metal covered tapered axle ends to receive the skeins and skeins secured upon and inclosing said ends.
2. An axle comprising a wooden core with tapered ends and a thin metal sheath inclosing the core, its ends permanently wrapped around and set in position about the tapered ends of the core to form metal covered tapered axle ends to receive the skeins, such core projecting upwardly between the skeins and between the sides of the sheath.
3. An axle comprising a wooden core with tapered ends and a thin metal sheath inclosing the core, its ends permanently wrapped

around and set in position about the tapered ends of the core to form metal covered tapered axle ends to receive the skeins, the upper portions of the sheath between the skeins being grooved, crimped or ribbed.

4. An axle comprising a wooden core with tapered ends and a thin metal sheath inclosing the core, its ends permanently wrapped around and set in position about the tapered ends of the core to form metal covered tapered axle ends to receive the skeins, such core projecting upwardly between the skeins and between the sides of the sheath, the upper portions of the sheath between the skeins being grooved, crimped or ribbed.

5. An axle comprising a two part structure consisting of a wooden core with tapered ends, and a thin metal sheath inclosing the core, its ends permanently wrapped around and set in position about the tapered ends of the core to form metal covered tapered axle ends to receive the skeins and skeins secured upon and inclosing said ends, and transverse securing pieces through axle and sheath.

6. An axle comprising a wooden core with tapered ends and a thin metal sheath inclosing the core, its ends permanently wrapped around and set in position about the tapered ends of the core to form metal covered tapered axle ends to receive the skeins, such core projecting upwardly between the skeins and between the sides of the sheath, and transverse securing pieces through axle and sheath.

7. An axle comprising a wooden core with tapered ends, and a thin metal sheath inclosing the core, its ends permanently wrapped around and set in position about the tapered ends of the core to form metal covered tapered axle ends to receive the skeins, the upper portions of the sheath between the skeins being grooved, crimped or ribbed, and transverse securing pieces through axle and sheath.

8. An axle comprising a wooden core with tapered ends and a thin metal sheath inclosing the core, its ends permanently wrapped around and set in position about the tapered ends of the core to form metal covered tapered axle ends to receive the skeins, such core projecting upwardly between the skeins and between the sides of the sheath, the upper portions of the sheath between the skeins being grooved, crimped or ribbed, and transverse securing pieces through axle and sheath.

9. An axle comprising a two part structure consisting of a wooden core with tapered ends, and a thin metal sheath inclosing the core, its ends permanently wrapped around and set in position about the tapered ends of the core to form metal covered tapered axle ends to receive the skeins and skeins secured upon and inclosing said ends, and a

bolt driven into the core ends and adapted to hold the skeins in position.

10. An axle comprising a wooden core with tapered ends, and a thin metal sheath inclosing the core, its ends permanently wrapped around and set in position about the tapered ends of the core to form metal covered tapered axle ends to receive the skeins, such core projecting upwardly between the skeins and between the sides of the sheath, and a bolt driven into the core ends and adapted to hold the skeins in position.

11. An axle, comprising a core containing uniformly compressible tapered wooden ends, and a thin metal sheath wrapped about and inclosing such tapered ends to form yielding ends and skeins forced onto such tapered wood-filled inclosed ends.

12. An axle comprising a wooden core with uniformly compressible tapered ends and a thin metal sheath inclosing the core, its ends permanently wrapped around and set in position about the tapered ends of the core to form metal covered tapered axle ends to receive the skeins and skeins secured upon and inclosing said ends.

13. An axle comprising a wooden core with uniformly compressible tapered ends, and a thin metal sheath inclosing the core, its ends permanently wrapped around and set in position about the tapered ends of the core to form metal covered tapered axle ends to receive the skeins and skeins secured

upon and inclosing said ends, and transverse 35 securing pieces through axle and sheath.

14. An axle comprising a wooden core with uniformly compressible tapered ends, and a thin metal sheath inclosing the core, its ends permanently wrapped around and 40 set in position about the tapered ends of the core to form metal covered tapered axle ends to receive the skeins and skeins secured upon and inclosing said ends, and a bolt driven into the core ends and adapted to hold the 45 skeins in position.

15. An axle comprising a thin sheet metal sheath, its ends tapered and capable of uniform compression, with a compressible filling within such ends, and a skein adapted to 50 be forced onto such end so as to compress the same.

16. An axle comprising a central or body portion with two tapering ends each consisting of a uniformly compressible tapered 55 core, a uniformly compressible sheet metal covering for such core, and a skein forced onto such end.

17. An axle comprising a core containing homogeneous tapered ends, a thin metal 60 sheath wrapped about and inclosing such tapered ends so as to form uniformly yielding ends, and skeins forced upon such tapered homogeneous inclosed ends.
